UNITED STATES PATENT OFFICE.

CHARLES GLOEKLER, OF PITTSBURG, PENNSYLVANIA.

DESIGN FOR A MEAT-RACK.

SPECIFICATION forming part of Design No. 17,796, dated October 18, 1887.

Application filed August 12, 1887. Serial No. 246,810. Term of patent 7 years.

To all whom it may concern:

Be it known that I, CHARLES GLOEKLER, a citizen of the United States, residing in Pittsburgh, in the county of Allegheny and State of Pennsylvania, have invented and produced a new and original Design for a Meat-Rack; and I do hereby declare that the following is a full and exact description of the same, reference being had to the accompanying drawings, forming a part thereof.

The leading features of my design are the upwardly and inwardly turned scroll form given to the ends of the hook-rails, the double inwardly-turned scroll form given to the rear ends of the brackets, and the reverse scroll ornaments on the upper rail, the inner scroll being larger than the outer scroll of each ornament.

In the drawings, A A are the hook-rails, B B the brackets, and C C the double-scroll ornaments on the upper rail. The hook-rails A A have upwardly and inwardly turned scrolls a a, more slender than the body of the rail, as shown. The brackets B B have double scrolls b b, turned inward toward each other at the rear end of each bracket, as shown. The double-scroll ornaments C C on the upper rail have reverse scrolls c c—that is, the scrolls at the two ends are turned in opposite directions—and the inner scroll of each has a larger size or diameter than the outer scroll, as shown.

I claim—

The design for a meat-rack herein shown and described, the same consisting of the hook-rails having the upwardly and inwardly turned scrolls a a at the ends, the double inwardly-turned scrolls b b at the rear ends of the brackets, and the ornaments having reverse scrolls c c at the two ends, the inner scroll being larger than the outer scroll.

In witness whereof I have hereunto signed my name in the presence of two subscribing witnesses.

CHARLES GLOEKLER.
